(57) **CLAIM**

The ornamental design for a hand held device capable of communicating audio and video data, as shown and described.

DESCRIPTION

FIG. 1 is a perspective view of my design;

FIG. 2 is a right side view of my design;

FIG. 3 is a left side view of my design;

FIG. 4 is a front view of my design;

FIG. 5 is a top view of my design;

FIG. 6 is a bottom view of my design; and,

FIG. 7 is a rear view of my design.

The broken lines are for illustrative purpose only and form no part of the claimed design.
